FOOTWEAR

Benjamin Benjamin, Forest Hills, N. Y., assignor to General Shoe Corporation, Nashville, Tenn., a corporation of Tennessee

Application November 30, 1954, Serial No. 472,190

2 Claims. (Cl. 36—24.5)

This invention relates generally to footwear and more particularly to ladies' shoes and methods of manufacturing the same.

In the design and production of feminine shoes and style, for example the sling pump type, one feature which detracts from the appearance thereof is the fact that the insole lies on top of the heel in a separate layer.

It is accordingly a principal object of the present invention to provide a shoe in which there is no apparent inner sole above the heel seat and wherein the heel seat part of the inner sole has been merged or blended into the heel.

Another object of the present invention resides in the provision of a shoe in which the heel appears as a virtual extension of the shank portion of the shoe.

A still further object of the present invention is the production of a shoe having a new appearance with the thin pencil line of the heel top unmarred by any layer above it.

Other objects of the present invention are to provide a shoe bearing the above objects in mind which is of simple construction, inexpensive to manufacture, has a minimum number of parts, is easy to assemble and efficient in wear.

For other objects and a better understanding of the invention, reference may be had to the following detailed description taken in connection with the accompanying drawing, in which:

Figure 1 is a perspective view of a preferred embodiment of the present invention;

Fig. 2 is a fragmentary side elevational view of a conventional shoe, illustrating the manner in which the inner sole lies on top of the heel in a separate layer as contrasted with the showing of Fig. 1;

Fig. 3 is a side elevational view shown alone of the heel forming a part of the present invention;

Fig. 4 is a front elevational view thereof looking along the line 4—4 of Fig. 3;

Fig. 5 is a bottom plan view thereof;

Fig. 6 is a vertical sectional view thereof taken along the line 6—6 of Fig. 4;

Fig. 7 is a longitudinal sectional view taken along the line 7—7 of Fig. 1;

Fig. 8 is a transverse sectional view taken along the line 8—8 of Fig. 1;

Fig. 9 is a transverse sectional view taken along the line 9—9 of Fig. 1;

Fig. 10 is a side elevational view of the inner sole shown formed with the bevelled or skived portion received within the top of the heel;

Fig. 11 is a transverse sectional view thereof taken along the line 11—11 of Fig. 10;

Fig. 12 is a perspective view of the inner sole showing the covered heel attached thereto according to one method of fabrication and showing the steel shank in operative position;

Fig. 13 is a perspective view showing the heel, shank and inner sole of Fig. 12 attached to the last and illustrating the next step in the manufacture;

2

Fig. 14 is a perspective view of the last, showing the inner sole alone and shank attached thereto, according to another method of manufacture;

Fig. 15 is a view similar to Fig. 14 and showing the next step in the method of manufacture wherein the shoe lining and covering are attached; and

Fig. 16 is a view similar to Fig. 15 but showing the next step in the manufacture according to the second method and showing the outer sole attached at the ball portion of the shoe and split into three separable layers at its rear portion just prior to insertion and securing of the heel.

Briefly stated, the invention contemplates a shoe in which the heel seat portion of the inner sole is skived or bevelled towards its peripheral edges so that during the manufacturing process this portion can be received by the cupped-out heel top which has been previously recessed, as well as methods of producing a shoe incorporating these features.

Referring now more in detail to the drawing, and more particularly to Fig. 2, 10 indicates generally a shoe of the sling pump type including the usual shoe upper 11, inner sole 12, heel 13, outer sole 14 and heel tip 15, substantially as illustrated. It will be noted that the heel seat portion of the insole 12 lies on top of the heel 13 in a separate layer, detracting from the appearance thereof.

In the practice of my invention, there is provided a shoe indicated generally at 16 wherein there is no apparent inner sole above the heel seat and wherein the heel seat part of the inner sole has been merged or blended into the heel, imparting a new appearance to the shoe with the thin pencil line of the heel top unmarred by any layer above it. It will also be noted from Fig. 1 that the heel appears as a virtual extension of the shank portion of the shoe.

In achieving this construction, I provide a heel indicated generally at 17 of conventional shape and including the breast portion 18. However, the top of the heel is dished out providing a concave recess 19 extending inwardly and downwardly from a substantially U-shaped, coplanar, peripheral edge 20, for a purpose which will hereinafter become clear (Figs. 3 through 6). For the accomplishment of the present invention, the recess 19 at its deepest point extends downwardly about $\frac{3}{32}$ or one-quarter of an inch below the planar peripheral edge 20.

In the further practice of my invention, I provide an insole indicated generally at 21 (Fig. 10) including a ball portion 22, a shank 23 and a thickened heel seat portion 24, the undersurface of the heel seat portion 24 being bevelled or skived (Fig. 11) so as to present a smoothly rounded, convex portion or surface 25 extending inwardly and downwardly from the peripheral side and rear edges thereof and adapted to fit within the recess 19 of the heel. It will be noted that the upper surface 26 of the heel seat portion is flat and lies within the same plane as the peripheral edge 20 of the heel when the insole and heel are in the assembled relationship of Fig. 7.

As shown in Fig. 12, the ball part 22 of the insole 21 is conventionally dished out as at 27 and receives there-within the usual filler 28.

An inflexible shank 29 is then secured to the undersurface of the shank portion 23 and heel seat portion 24 by means of nails 30, the shank 29 being formed of steel or other suitable material.

According to the first method of manufacturing the shoe, the heel 17 (Fig. 7) is then secured to the shank 29 and insole 21 by means of the screw 31 and nails 32, the rear end of the shank and the convex undersurface 25 of the heel seat portion of the insole being received within the recess 19 with the upper surface 26 of the heel seat portion lying in the same plane as the peripheral edge 19 of the heel. Thus, the heel seat portion 24 of the

shank is merged or blended into the recess and the insole does not appear as a separate layer on top of the heel, as in the conventional shoe of the Fig. 2, and imparting a new appearance with the thin pencil line of the heel top unmarred by any layer above it.

Edging 33 is then cemented to the marginal edges of the shank 23 and ball portion 22 of the insole 21, extending back to the heel seat portion 24.

Heel covering material 34 is then cemented to the heel 17 with the marginal edges 35 thereof partially covering the breast portion and the rear portion of the shank 23 of the insole (Fig. 12).

The usual rubber or leather heel 36 is then secured to the bottom of the heel 17.

The resulting heel and insole assembly is then attached to a conventional last indicated generally at 37 by means of nails 38 and the usual set screw member 39, as shown in Fig. 13. The last 37 includes the usual holder 40 and plate 41.

The heel and insole assembly is then finished in the usual manner with the outer sole 42, sock lining 43 and shoe upper 44 including the usual shoe lining 45 to produce the finished product of Fig. 1.

As a second method of assembly, sequential stages of which are illustrated in Figs. 14, 15, and 16, the insole 21 having the dished out portion 27 to which the filler 28 has been applied, the edging 33 cemented to the marginal edges thereof, and the shank 29 secured thereto is applied to the last 37 in the usual manner without the attachment thereto of the heel 17. It will be noted that, as in the first method, the insole 21 includes the usual thickened portion 24 having the convex undersurface 25 and flat upper surface. Thus, this first step in this second method is as shown in Fig. 14.

In the next step, as shown in Fig. 15, the lining 45 and shoe upper 44 are cemented to the insole 21 in the usual manner, the lining 45 being secured to the last 37 by nails 46.

According to this second method of assembly, a modified outer sole indicated generally at 47 is provided and includes a ball portion 48 and a shank portion 49. The heel seat portion of the outer sole 47 and the upper portion of the shank portion 49 thereof is split, as shown in Fig. 16, providing an inner layer 52 which extends across the shank 29, an intermediate shortened and slotted portion 51 and an outer layer 50 adapted to cover the breast 18 and marginal edges 35 of the heel 17. The inner layer 52 is secured to the insole across the shank 29 by means of the nails 53 while the upper surface of the shank portion 49 and ball portion 48 are cemented to the bottom of the assembly. The inner layer 52 of the outer sole 47 is complementarily bevelled or skived in the same manner as the heel seat portion of the insole 21 and the two, with the end of the shank 29 mounted therebetween, are fitted into the cupped out portion or recess 19 of heel 17, which latter is then secured thereto in the usual manner. It will be noted that the intermediate layer 51 is received intermediate the heel 17 and inner layer 52, providing a firmer structure, while the outer layer 50 is then cemented to the breast portion of the heel and finished in the usual manner. The shoe is then finished in the usual manner including the cementing in of the sock lining 23.

The finished shoe according to both methods and as shown in Fig. 1 has a strikingly new appearance with the thin pencil line edge of the heel being unbroken by any unsightly layer of insole at the top. Furthermore, there is no danger of breakage due to the inherent strength of the built-in metal shank 29.

It is to be understood that while a sling pump type of shoe has been shown in the drawing, this is for illustrative purposes only and is not to be deemed limitative in any sense.

It should now be apparent that there has been provided a shoe in which the heel appears as a virtual extension of the shank portion of the shoe. It should also be apparent that there has been provided a shoe in which there is no apparent inner sole above the heel seat and wherein the heel seat part of the inner sole has been merged or blended into the heel to present a shoe having a strikingly new appearance with the thin pencil line of the heel top unmarred by any layer above it.

While various changes may be made in the detail construction, it shall be understood that such changes shall be within the spirit and scope of the present invention as defined by the appended claims.

What is claimed is:

25 1. In a lady's shoe having a heel, an insole and an open back upper exposing the interior of the shoe in the region of the heel, said insole including an integral shank and ball portion of substantially the same thickness and an integral heel seat portion thicker than said shank and ball portion, said thickened heel seat portion having a convex under surface and a flat upper surface with such surfaces intersecting at the side and rear edges of the heel seat portion, said heel having a concave upper surface with the side and rear edges thereof bounding such concave surface being formed by the intersection of the concave surface with the side and rear walls of the heel, said heel seat portion being received by said heel with said convex under surface disposed adjacent said concave upper surface and with the flat upper surface of the heel seat portion lying in the same plane as the upper side and rear edges of the heel whereby when the heel assembly is viewed in side elevation, the upper edge of the heel is unmarred by any layer of insole above it.

45 2. In the lady's shoe according to claim 1, wherein the side and rear edges of said heel bounding said recess are coplanar and taper to a sharp edge, said heel seat portion having a flat upper surface lying in substantially the same plane as the side and rear edges of the heel and having an under surface tapering peripherally to intersect the flat upper surface at the side and rear edges of the heel seat portion, said side and rear edges of the heel seat portion being disposed inwardly of and closely adjacent to the side and rear edges of the heel.
